UNITED STATES PATENT OFFICE.

WILLIAM CAMPBELL, OF NEW YORK, N. Y.

WALL-PAPER.

SPECIFICATION forming part of Letters Patent No. 351,962, dated November 2, 1886.

Application filed July 21, 1886. Serial No. 202,638. (Specimens.)

To all whom it may concern:

Be it known that I, WILLIAM CAMPBELL, of the city, county, and State of New York, have invented a new and Improved Wall-Paper, of 5 which the following is a full, clear, and exact description.

My invention consists, principally, of a "flock" surface wall-paper showing a figure or design, and having a single continuous layer 10 of flock of one color.

The invention also consists of the method of producing such paper, all as hereinafter described and claimed.

Reference is to be had to the accompanying 15 drawings forming a part of this specification, in which the figure is an illustration of my new wall-paper and the method of ornamenting it.

The paper A is first printed with a design, 20 *b*, of any color or colors, and the paper may have a ground, *c*, of any color. Over the whole surface of the paper is then spread a thin coat, *d*, of transparent sizing or glue. Upon this layer or coating of glue, before the 25 same is dry, is cast a continuous coating, *e*, of fine wool felt of a single color. The fine wool felt is disposed thinly over the whole design

and ground or body of the paper, and gives a continuous flock surface, through which the design appears. In this manner I am enabled 30 to produce a figured flock-paper very cheaply with a flock of one color, and the ground and figure both showing through a flock of a different color gives the paper a very rich appearance.

Having thus fully described my invention, I claim as new and desire to secure by Letters Patent—

1. As a new article of manufacture, wall-paper having a design or figure printed thereon, and having a continuous surface of flock of a single color, through which the design appears, substantially as described. 40

2. The method herein described of producing flock-surface paper, which consists in first 45 printing the paper with a figure or design, then coating the entire surface with glue, and finally applying flock to the entire glue coated surface, substantially as described.

WILLIAM CAMPBELL.
